UNITED STATES PATENT OFFICE.

ARTHUR KITSON, OF PHILADELPHIA, PENNSYLVANIA, ASSIGNOR TO THE KITSON HYDROCARBON HEATING AND INCANDESCENT LIGHTING COMPANY, OF SAME PLACE AND CHARLESTON, WEST VIRGINIA.

THERMOSTATIC VALVE FOR VAPOR-TUBES.

SPECIFICATION forming part of Letters Patent No. 665,110, dated January 1, 1901.

Application filed December 7, 1899. Serial No. 739,470. (No model.)

To all whom it may concern:

Be it known that I, ARTHUR KITSON, a subject of the Queen of Great Britain, and a resident of Philadelphia, (Germantown,) county of Philadelphia, State of Pennsylvania, have invented certain new and useful Improvements in Vaporizing-Tubes, of which the following is a specification.

My invention relates to automatic cut-outs for vapor-burning apparatus; and more specifically it consists of a thermostatic valve so constructed and located as to operate automatically and shut off the flow of oil to the vaporizing-chamber of the apparatus when the flame goes out.

In the various forms of apparatus burning the vapor of a fluid hydrocarbon supplied under pressure to the vaporizer a certain degree of difficulty has been encountered when the apparatus was left in the care of unskilled persons, said difficulty arising from the fact that if for any reason the lamp or stove goes out through the stopping up of the discharge-orifice for the jet of vapor or by the flooding of the vaporizing-chamber with such large quantity of oil as reduces its temperature below the vaporizing-point oil will continue to flow slowly into the apparatus and a considerable amount thereof is wasted or discharged upon the furniture or contents of the room, ruining the same. The object of my invention is to automatically prevent this, and it accomplishes it by means of a thermostatic valve, which is normally closed at atmospheric temperature, thereby cutting off all flow of oil, and only opens to admit oil to the vaporizing-chamber when the temperature of the same has been raised to the point of vaporization or nearly to said point.

The preferred form of apparatus embodying my invention is illustrated in the accompanying sheet of drawings, in which—

Figure 1 is a central section of a vaporizing-tube with my invention applied thereto. Fig. 2 is a cross-section on line $s^1 s^2$ of Fig. 1. Fig. 3 is a similar cross-section on line $s^3 s^4$ of Fig. 1. Fig. 4 is a similar cross-section on line $s^5 s^6$ of Fig. 1.

Throughout the figures of the drawings like reference-figures refer to like parts.

The vaporizing-tube 1 is connected to the oil-supply pipe 3 by means of the threaded union 2 in the well-known way. The supply-pipe 3 is controlled by any suitable form of valve 4 which is capable of accurate adjustment to prevent the discharge of oil under pressure or to permit the same at a slow rate of speed. The end of the vaporizing-tube at which the oil is admitted is preferably made in the form of a casting 5, having a tapering valve-seat formed therein for the correspondingly-tapered needle-valve 6. The outer end of the casting 5 is threaded to receive the screw-plug 7, which when removed gives access to the interior of the needle-valve chamber thus formed. The outer end of the needle-valve plunger is slotted, as shown at 8, or otherwise shaped so that it can be grasped firmly by a proper tool when it is desired to rotate it.

Within the body of the vaporizing-tube and preferably concentric with the axis thereof is a rod or filler 9, which is fastened to the plug 10, closing the other end of the vaporizing-tube—that is to say, the end having the discharge-orifice 11 for the jet of vapor. This rod 9 is preferably made hollow throughout nearly all of its length, as shown at 12, and is made of some metal, such as copper, which expands at a higher rate than does the steel or iron of which the vaporizing-tube is made. Preferably the rod 9 is fastened to the other end of the vaporizing-tube by screwing into the plug 10, and at its free end it has a fine hole drilled into it and threaded, into which the threaded end 13 of the plunger 6 of the needle-valve may be screwed. This forms an adjustable connection between the needle-valve plunger and the thermostat 9.

Several gauzes 14 15 may be inserted in the vaporizing-tube and arranged concentrically about the thermostat-rod 9, serving to help center the same in the vaporizing-tube.

The mode of operation of my invention is as follows: The vaporizing-tube being inserted in the lamp or other vapor-burning apparatus, the connection of the valve-plunger 6 with

the thermostat 9 is so adjusted by turning the said plunger 6 and screwing it a greater or less distance into the rod 9 that the needle-valve formed by the parts 5 and 6 is closed 5 and all access of oil to the vaporizing-tube prevented. When, however, the preheating of the vaporizing-tube by the flame of a torch or of a Bunsen burner is brought about in any one of the well-known ways for the purpose 10 of starting the lamp into operation, the rod 9 will expand faster than the vaporizing-tube 1, and the plunger 6 of the needle-valve will be lifted a sufficient distance from its seat to permit oil to pass through to the vaporizing tube 15 or chamber in the requisite quantity. The controlling-valve 4 is then opened, and the oil under pressure passes into the vaporizing tube or chamber 1 and is there turned into vapor, issuing from the orifice 11 in the form of a jet. 20 The vapor thus formed is burned in the vapor-burner in the well-known way, and the heat of the burner maintains the tube 1 at the necessary temperature for continued vaporization of the oil. So long as this temperature is maintained 25 the thermostat-valve is open. If, however, the lamp goes out for any reason whatever, the vaporizing-tube and its contained thermostat cool down and the thermostat acts to automatically close the needle-valve and 30 prevent further flow of oil. If the contraction of the thermostat stretches the parts so that the needle-valve opens to an unnecessary extent when the lamp is in operation or does not close tightly when it is out of operation, 35 the trouble can be remedied by removing the screw-plug 7 and using a small screw-driver to rotate the plunger 6, thereby taking up the adjustable screw-threaded connection of said plunger with the thermostat to a degree which 40 will put the parts in proper relation for renewed successful operation.

To prevent premature opening of the valve and the resulting flooding of the vaporizing chamber, connections, &c., the valve should 45 be adjusted to remain closed until the vaporizing-tube has been raised to the temperature necessary to vaporize the oil, and as this point of valve-opening can only be determined by actual tests the valve and thermostat sections 50 are, therefore, adjustably connected in the manner described to enable the valve to be readily adjusted and properly set to open at a predetermined temperature.

The advantages of my invention are of course in the saving of the waste of oil and in the prevention of damage by such waste oil and also in removing all danger of fire which might result from trying to start up the lamp when it was full of oil and surrounding 55 objects were saturated with the same. Moreover, while my invention accomplishes the above objects automatically and effectively it adds but little to the cost of the lamp and is entirely hidden and self-contained within 60 the ordinary lamp apparatus. It is also readily adjustable and does not in any way inter-

fer with the ordinary manipulation of the lamp parts.

It is evident of course that various changes could be made in the details of construction 70 illustrated without departing from the spirit and scope of my invention so long as the principle of operation described in the specification or the general relative arrangement of parts illustrated in the drawings is preserved. 75 Other forms of thermostat might be employed, and different forms of valve might be substituted. The thermostat might be differently located so long as it is within the heating zone of the lamp-burner and of the preheating device. The feature of hollowing out the thermostat-rod might be dispensed with, though I prefer the hollow form, as it economizes material without sacrificing stiffness of the rod and also renders the thermostat more susceptible to variations in temperature, as of course the amount of heat necessary to raise the thermostat to a given temperature decreases as the amount of material to be heated decreases. 85

Having therefore described my invention, what I claim as new, and desire to protect by Letters Patent, is—

1. In combination with the vaporizing-chamber of a vapor-burning apparatus, an adjustable thermostatic valve controlling the flow of oil to said vaporizing-chamber and thermostatically closed normally, all the adjustable parts of the thermostatic valve being 95 inclosed by the walls of the vaporizing-chamber, but so located that the heat employed to raise the chamber to the temperature of vaporization will cause said thermostatic valve to open.

2. In combination with the vaporizing-tube 105 of a vapor-burning apparatus, a valve located in one end of said tube and opening outward, a rod of metal whose ratio of expansion under heat is greater than that of the metal of which the vaporizing-tube is composed, 110 having one end fastened in the head of the tube opposite to that in which the valve is located, and the connection between the valve-plunger and said rod.

3. In combination with the vaporizing-tube 115 of a vapor-burning apparatus, a normally-closed valve located in one end of said tube and opening outward, a rod of metal whose ratio of expansion under heat is greater than that of the metal of which the vaporizing-tube is composed, 120 having one end fastened in the head of the tube opposite to that in which the valve is located and the adjustable screw-threaded connection between the valve-plunger and said rod.

4. In combination with the vaporizing-tube 125 of a vapor-burning apparatus, a normally-closed valve located in one end of said tube and opening outward, a hollow rod of metal whose ratio of expansion under heat is greater 130 than that of the metal of which the vaporizing-tube is composed, having one end fastened

in the head of the tube opposite to that in which the valve is located, and the connection between the valve-plunger and said rod.

5. The combination of the vaporizing-tube provided with a needle-valve seat at the inlet end, the needle-valve plunger with a slotted outer end and threaded inner end, the screw-plug giving access to the slotted end of the plunger, the thermostat attached to the other

end of the vaporizing-tube and adjustably connected to the needle-valve plunger by the aforesaid threaded end thereof.

Signed by me at New York, N. Y., this 24th day of November, 1899.

ARTHUR KITSON.
